HEAT EXCHANGE APPARATUS

Reinhold Dietze, Goechwitz, Germany

Application October 2, 1937, Serial No. 167,064
In Germany January 5, 1937

9 Claims. (Cl. 263—22)

This invention relates to heat exchange apparatus and more particularly to improvements in rotary kilns for the burning, calcining, roasting, and sintering of various kinds of materials. It is the principal object of the invention to increase the output and improve the efficiency of kilns to the end that operating expenses may be reduced and the product of the kiln rendered more uniform and otherwise improved. It has heretofore been proposed to provide the interior of rotary kilns for the burning of cement or the like with a longitudinally extending wall or partition so as to divide the kiln into two chambers, on the theory that such a partition would absorb heat from the hot kiln gases and transmit this heat to the material passing through the kiln. Such an arrangement has never been adopted in practice, however, since the improvement in efficiency of the kiln resulting therefrom is negligible. Failure of such walls to assist in the exchange of heat can probably be explained by the fact that there is little tendency for the hot gases to circulate within and about the kiln or to break away from the intermediate wall; consequently only a relatively small portion of the hot gases actually contacts this wall.

In accordance with the present invention it is proposed to provide a plurality of walls or partitions interiorly of the kiln, such partitions extending generally longitudinally of the kiln and being spaced in the direction of the length thereof, the successive partitions being so disposed as to occupy different positions with respect to the axis of the kiln. For example, in one arrangement, the partitions may be diametrically disposed, the successive partitions being arranged in increasingly greater angular relation with the first partition, so that the whole series of partitions forms in effect an interrupted helix. It will be apparent that with such a construction different portions of the stream of hot gas are contacted by the successive partitions. Again, there is a tendency, when a helical arrangement of the partitions is employed, to cause the hot gases to follow a generally helical path, and the swirling motion thus set up results in the contacting of the partitions and the material being fed through the kiln by a greater volume of the hot gases.

It is also found that a kiln equipped with longitudinally spaced and offset, staggered or helical partitions ensures that the hot gases are brought into contact with the whole of the material passing through the kiln and not only with the surface layer thereof, the partitions being effective

to agitate the material and to break it up and shower it down through the current of gas.

It has been found in the application of the principles of the instant invention to a cement kiln, that it is not only possible to effect an increase in the kiln output of 18% and a fuel saving of 14%, but that the formation of deposits on the wall of the kiln, commonly referred to as rings, is avoided, these deposits normally resulting from the failure of the kiln to effectively dry, preheat, and otherwise condition the material before it enters the principal sintering zone.

Further objects and features of the invention will be apparent from the following description taken in connection with the accompanying drawings, in which

Figure 1 is a longitudinal sectional view of a rotary kiln constructed in accordance with the present invention;

Figure 2 is a transverse sectional view taken substantially on the line 2—2 of Figure 1;

Figures 3, 4, and 5 are transverse sectional views corresponding to Figure 2 and illustrating modified forms of partition;

Figure 6 is a longitudinal sectional view of a kiln illustrating a further modified form of partition;

Figure 7 is a horizontal section on the line 7—7 of Figure 6; and

Figure 8 is a transverse sectional view on the line 8—8 of Figure 6.

Referring first to the form of the invention shown in Figures 1 and 2, numeral 10 indicates a rotary kiln of any conventional type, means for feeding material to be treated, for example cement, into one end of the kiln being indicated at 11. At the discharge end of the kiln a fuel nozzle 12 may be provided, whereby hot gases may be caused to flow through the kiln in a direction opposite to that in which the material is moved. It will be appreciated that the details of these elements form no part of the instant invention and that the construction of the kiln and its accessories may be modified as desired to suit the material undergoing treatment and the nature of the process applied thereto.

As hereinbefore indicated, the invention resides in the provision of a plurality of walls or partitions 15 which are diametrically or otherwise chordally disposed within the kiln 10, these partitions being spaced lengthwise of the kiln and being angularly related or otherwise offset as viewed endwise of the kiln so as to define different longitudinal planes. As shown more particularly in Figure 2, the successive partitions are prefera-

bly arranged at a constantly increasing angle so as to define a generally helical path, a swirling motion being thereby imparted to the hot gases as they move through the kiln. As pointed out above, this arrangement is found to be most effective in agitating, turning over, and breaking up the material, so as to present different strata of the material to the stream of hot gas.

In Figures 1 and 2, the partitions illustrated are of substantially uniform thickness and length, and are uniformly spaced and angularly disposed. It will nevertheless be appreciated that considerable modification of this arrangement may be effected without sacrificing the advantages derived from the invention. For example, each partition may be formed as indicated at 16 in Figure 3, to provide a concave surface 17 on either side thereof. Alternatively, a plurality of partitions may be disposed in contiguous relation to provide more than two passages for the hot gases. Reference is made in this connection to Figure 4 in which the kiln 10 is provided with partitions 18 and 19, each of which may be arcuate in transverse section, these partitions defining chambers 20, 21, and 22.

In Figure 5 of the drawings is illustrated a partition 25 of which the lateral surfaces are ribbed or corrugated as at 26 to form projections and depressions, this type of surface facilitating the transfer of heat into the partition and effecting greater agitation of the material as it passes through the kiln. If desired the partitions may be apertured to permit passage of gas through as well as along the same.

The construction shown in Figures 6 to 8 is quite similar to that illustrated in Figures 1 and 2, with the exception that each of the partitions is twisted or formed generally helically, this construction serving to increase the tendency of the hot gases to rotate, swirl, or follow a helical path in passing through the kiln, with resulting increase in efficiency.

In order to aid in an understanding of the invention, specific language is employed herein to describe the several embodiments thereof illustrated in the drawings. It will nevertheless be appreciated that various further modifications and alterations of these structures are contemplated such as fall within the spirit and scope of the invention as defined in the appended claims.

Having thus described the invention, what is claimed as new and desired to be secured by Letters Patent is:

1. In heat exchange apparatus, the combination with a rotary kiln, of a plurality of longitudinally spaced and generally longitudinally extending partitions disposed interiorly of said kiln,

transverse sections of successive partitions defining increasing angles with the first partition to form in effect an interrupted helix.

2. In heat exchange apparatus, the combination with a rotary kiln, of means for passing hot gas through said kiln, and means within said kiln for deflecting said gas to cause the same to describe a generally helical path within said kiln.

3. A rotary kiln having a generally longitudinally extending helical partition therein. 10

4. A rotary kiln having a series of diametrically disposed, generally longitudinally extending partitions therein, said partitions being spaced lengthwise of said kiln, successive partitions being arranged in increasing angular relation to the first partition to form in effect an interrupted helix, each partition being of generally helical shape. 15

5. In heat exchange apparatus, the combination with a rotary kiln, of a plurality of longitudinally spaced and generally longitudinally extending partitions disposed interiorly of said kiln, said partitions being offset with respect to each other as viewed endwise of the kiln, the lateral surfaces of said partitions being curved. 20

6. In heat exchange apparatus, the combination with a rotary kiln, of a plurality of longitudinally spaced and generally longitudinally extending partitions disposed interiorly of said kiln, said partitions being offset with respect to each other as viewed endwise of the kiln, said partitions having openings therein to permit passage of gas therethrough. 25

7. A rotary kiln having a plurality of longitudinally spaced, chordal partitions supported at the lateral ends thereof on the kiln wall to afford substantially free passages for gas at each side thereof. 30

8. A rotary kiln having a series of diametrically disposed, generally longitudinally extending partitions therein, said partitions being spaced lengthwise of said kiln and being supported at the lateral ends thereof on the kiln wall to afford substantially free passages for gas at each side thereof. 40

9. A rotary kiln having a series of diametrically disposed, generally longitudinally extending partitions therein, said partitions being spaced lengthwise of said kiln, successive partitions being arranged in increasing angular relation to the first partition to form in effect an interrupted helix, said partitions being supported at the lateral ends thereof on the kiln wall to afford substantially free passages for gas at each side thereof. 45
